UNITED STATES PATENT OFFICE.

CHARLES F. BENNETT, OF CHICAGO, ILLINOIS, ASSIGNEE TO SHARP & SMITH, OF CHICAGO, ILLINOIS, A CORPORATION OF ILLINOIS.

SUPPORTER.

1,169,455.

Specification of Letters Patent. Patented Jan. 25, 1916.

Application filed August 26, 1915. Serial No. 47,517.

To all whom it may concern:

Be it known that I, CHARLES F. BENNETT, a citizen of the United States, residing at Chicago, in the county of Cook and State of Illinois, have invented a new and useful Improvement in Supporters, of which the following is a specification.

My invention relates to certain new and useful improvements in supporters and is 10 fully described and explained in the specification and shown in the accompanying drawings, in which:—

Figure 1 is a perspective view of my improved supporter, and Fig. 2 is a section on 15 the line 2 of Fig. 1.

Referring to the drawings, 3 is an elastic belt to the front of which is attached a pouch 4 terminating in thigh circlets 5. The pouch is preferably made in the manner set forth 20 in my expired Patent No. 594,673, that is, of two separate pieces of material attached together in the front, so that the pouch is of twice the width of the material, crossed over at the bottom to form a square bottom 25 for the pouch and continued to form the thigh circlets. As far as the present invention is concerned, however, this construction of the pouch is not essential as other modes of construction might be adopted and the 30 material might be varied considerably. It is common practice for instance to make the pouches of some supporters of linen or cotton mesh, which is relatively inelastic, and this can be done, as far as the present invention 35 is concerned, although the preferred construction is that illustrated, where the pouch and thigh circlets are made of the same material and are therefore, of course, elastic throughout.

40 My present construction differs from that of my prior patent in that the thigh-circlets, instead of being attached to the rear of the belt as therein specified, are attached to the belt in line with the upper parts of the lateral edges of the pouch. This produces a 45 number of advantages of operation which it has heretofore been impossible to secure. It was found in the use of the jock strap of my prior patent referred to, that it was desirable 50 gradually to move the thigh circlets nearer to the front. This resulted in a better fit, because the upper ends of the thigh circlets pull backward on the front of the belt, holding the pouch more snugly against 55 the body. It was found also, however, that

as the thigh circlets were brought forward and approached the edges of the pouch, the strain was concentrated upon a small part of the belt which very quickly gave out. I have tried supporters made in accordance 60 with my prior patent where the thigh circlets were moved forward to about an inch on each side of the pouch and the devices so made proved entirely unsatisfactory because the elastic belt for the space of one 65 inch on the two sides of the pouch, that is, in the space between the ends of the thigh circlets and the pouch, quickly lost its elasticity and was destroyed. After many experiments it was found that the thigh circlets 70 could not be moved farther forward than about three inches from the two sides of the pouch and this became the commercial form. I have discovered, however, that by the present construction in which the thigh 75 circlets are secured directly to the lateral edges of the pouch, all the difficulties referred to are met and the device is peculiarly satisfactory. The pouch is held tightly 80 against the body, not only by the elastic pull of the belt, but by the pull of the thigh circlets. This results also in making the entire belt except the portion crossed by the pouch elastic, whereas, in the prior construction, the lower edge of the belt was rendered 85 inelastic in that part of its lower edge to which the thigh circlets were attached, that is, in practice about three inches of the lower margin of the belt on each side was inelastic and, of course, that part of the belt lying 90 under and attached to the pouch was inelastic. In other words out of the belt of about two feet in circumference nearly half was inelastic along its lower edge, and this threw the great strain upon the remaining 95 part of the belt causing it quite quickly to disintegrate. In the present device if the belt be two feet in circumference, 18 inches of it is elastic. Furthermore, by this construction the thigh circlets are more widely 100 separated, thereby more accurately fitting into the gluteal grooves of the wearer and leaving a wider space at the rear which is desirable for sanitary reasons.

I realize that considerable variation is 105 possible in the details of the construction herein shown, and I do not intend to limit myself thereto, except as pointed out in the following claim, in which it is my intention to claim all the novelty inherent in the de- 110

vice as broadly as is permitted by the state of the art.

I claim as new and desire to secure by Letters Patent:

- 5 A supporter comprising an elastic belt of such width and strength as to exert material pressure on the abdomen of the wearer, a pouch having its upper end crossing the belt and secured thereto, whereby the portion of the belt crossed by the pouch is rendered substantially inelastic, a pair of elastic thigh circlets secured at one end to the lower end of the pouch and extending rearwardly,

upwardly and forwardly therefrom and attached at their other ends to the inelastic portion of the belt, said elastic thigh circlets being of such width and strength as to add a material pressure to the inelastic portion of the belt on the abdomen of the wearer.

In testimony whereof I have hereunto set 20 my hand this 23rd day of August, 1915.

CHARLES F. BENNETT.
